UNITED STATES PATENT OFFICE.

FRANK L. DARLING, OF LONG BEACH, CALIFORNIA.

CRIMPED-CAP OPENER.

Application filed July 16, 1926. Serial No. 122,909.

My invention is a crimp cap opener, being incorporated with the cap to facilitate removing same from bottles or the like.

An object of my invention is to construct an opener for crimp caps connected thereto and attached with the cap to a bottle or the like, to facilitate the removal of the cap from the bottle.

A more specific object of my invention is the formation of an opener which will fit between the crimps of the cap and the upper end of the bottle neck so that on pulling of the opener the crimps are opened, allowing the ready removal of the cap.

Another specific object of my invention is to construct the opener so that it cannot come in contact with the liquid in the bottle.

In forming my crimp cap opener I preferably use a bent strip of wire having its free ends caught between the crimp of the cap and the upper end of a bottle neck, the ends being positioned above the cork or other packing which fits in the metallic bottle cap. The wire or strip may be loose if desired, or may be attached to the cap by grooves of the crimp being squeezed thereabout or by means of a small amount of solder or a slightly brazed connection.

My invention will be more readily understood from the following description and drawings, in which:

Figure 1 is a perspective view of a bottle neck with my crimp cap opener shown in connection with a crimp cap;

Fig. 2 is a vertical section substantially on the line 2—2 of Fig. 1 diametrically through a bottle, a crimp cap and my opener, showing same in the closed or sealed position;

Fig. 3 is a view similar to Fig. 2, showing the opener and cap in one of the stages of the opening procedure;

Fig. 4 is a view similar to Fig. 3, showing a further stage of the opening procedure;

Fig. 5 is an inverted perspective view of a cap with my opener attached thereto.

Figure 6 is a vertical section of a bottle and a cap with my opener, taken substantially on the line 6—6 of Fig. 9 prior to distorting the crimps of the cap, this figure showing the opener and cap in the normal position in which the article is marketed.

Figure 7 is a similar section showing the action of the opener in the initial stage of removing a cap.

Figure 8 is a section similar to Figs. 6 and

7 showing the cap loosened from the bottle.

Figure 9 is a section on the line 9—9 of Fig. 8 in the direction of the arrows, illustrating the squaring of the cap flange on 60 one side on levering upwardly on the opener.

Figure 10 is an underneath view of a cap to illustrate the fulcrum and leverage of the opener in acting on a bottle.

In the drawings, a bottle is designated by 65 the numeral 1, having a neck portion 2 with a bead 3 or the like adjacent the mouth 4 of the bottle. A crimp cap designated generally by the numeral 5 is generally of the ordinary construction, having a top 6 substantially flat and with a flange 7 having crimps 8 therein. A disc of packing material 9 such as cork or other suitable composition, is fitted between the upper edge of the mouth of the bottle and the top of the cap, 70 thus preventing the contents of the bottle coming in contact with the metal. The crimps are bent down over the bead in the ordinary manner.

My opener designated generally by the 80 numeral 10 comprises a strip 11 of material which may be wire, a flat band or anything of suitable material and shape. This is shown as having a reverse bend 12, the free ends 13 of which are bent underneath the 85 cork or other packing strip as indicated by the numeral 14 shown particularly in Fig. 5.

The strip or wire fits in crimps 15 so that it does not hold the cap flange spaced from the bottle, and if desired a small amount of solder indicated by the numeral 16, or a slight braze may secure the wire or strip to the flange of the cap. This latter connection however, is hardly necessary as the crimping of the cap holds the opening strip firmly in position against the bottle and is incorporated in position when the cap is seamed or placed on the top of the bottle.

In the manner of using my opener, the strip is pulled out from the bottle, it preferably being shaped to fit neatly against the upper end of the bottle as shown in Figs. 1 and 2 and in the first stage of opening will be pulled outwardly as shown in Fig. 3. This will act to bend the flange of the cap 105 outwardly, especially if the wire or strip is made of fairly stiff material, the opener functioning as a lever. In the further step shown in Fig. 4, it will be seen that the bent ends 14 extending over the packing 9 use 110 same as a fulcrum of a lever and pry the cap upwardly as indicated in Fig. 4.

In Fig. 6 it will be noted that the side element 11 of the opener extends upwardly underneath the bottle cap and that the ends 14 follow the junction of the top 6 of the cap and the flange 7, as shown in Fig. 5. The projecting part of the opener fits snug against the side of the bottle, as shown in Fig. 1. It will be seen by this construction taken with Fig. 5 that the wire or strip material forming the opener does not extend over the top of the bottle and hence does not cut into the packing 9 when the cap is crimped on the bottle but the ends 14 follow around the periphery of the packing on the outside of the portion forming the seal with the bottle.

When the lower end of the opener is given an initial pull to remove the cap, on account of the resilient material of the wire the crimps 15 in which the wire engages are pulled outwardly slightly and at the same time the ends 14 of the wire which engage the bottle cap are slightly distorted from the normal position shown in Fig. 6, this distortion being indicated by the numeral 17 in Fig. 7. On further levering up on the opener strip, the side of the cap flange between the two portions of the wire is to a certain extent straightened, as indicated by the numeral 18 in Fig. 9, this pulling the crimps between the two wires away from the bottle and also drawing the crimps slightly outside of the wire, as indicated by the numeral 19, away from the bead 3 of the bottle. When the flange of the cap at one side is clear of the bead, the ends 14, which have been compressed, due to their spring action return to their normal position and thrust upwardly on the top part of the cap, as indicated by the numeral 20 in Fig. 8. This gives a quick snap to the cap and aids its removal.

In Fig. 10 is illustrated a standard bottle cap giving the dimensions and showing the amount of leverage which my opener obtains. The cap, as illustrated, is $1\frac{1}{4}$ inches in diameter and the distance from the points 21, where the sides 10 of the opener engage the cap, and the line 22 of the ends of the bent portions 14 is $\frac{1}{8}$ inches. Thus on account of the circular curvature of the bottle cap and the portions 10 of the opener engaging at a considerable distance apart around the circumference, the fulcrum is substantially directly on the upper edge of the bottle or on the top of the packing, as illustrated in Fig. 4. The ends 14 exert a leverage on the cap from the fulcrum points 21 to their adjacent ends and hence materially aid in the ease with which a cap may be removed.

If the wire is merely held in the grooves of the crimps it will press against the top of the bottle when the free end is pulled out and thus raise the flange of the cap. In

the construction in which the wire or strip of the opener is secured to the cap by a small globule of solder or a point brazing, the action is substantially the same.

It is obvious that my opener may also be made of soft flexible wire or the like so that in the opening operation the wire will bend upwardly and expand the flange of the crimped cap sufficiently to allow air to enter below the packing and to allow easy removal of the cap.

An important feature of my invention is that the opener acts as a lever with the fulcrum end of the lever bearing on the top of the bottle or more correctly on the packing or cork which fits over the top. This gives a long leverage on the lower edge of the crimped flange and bends same outwardly. Hence my opener forms a satisfactory device with bottle caps which are made of stiff resilient metal in order to properly seal bottles which may generate gas or have the contents under pressure.

In my preferred construction I do not use any solder, the wire forming the opener being crimped by the crimps of the cap and the bent ends are fitted between the cork or packing and the metal of the cap, as shown in Fig. 5.

In the type of bottle caps illustrated, the hermetic seal is usually between the inner part of the neck of the bottle at the top and the cork or other packing, as clearly illustrated in Figs. 2 and 3. Hence the bent ends illustrated as at 14 do not pass across the top of the bottle neck and hence in sealing the bottle there is no danger of the packing being cut and moreover as the cap is tightly sealed on the bottle there is no danger of leakage adjacent the wire of the opener. My opener is also preferably made of stiff wire so that when being pulled upwardly in the position shown in Fig. 4 the wire levers on the upper periphery of the cork or packing, which pressure is transmitted to the rim of the bottle at the neck and the other part of the lever wire spreads the crimps on one side and levers the cap off the top of the bottle. It is to be noted that in my construction the two branches of the opener are spread a considerable distance apart, sufficient so that when the lever is pulled upwardly a sufficient number of the crimps are bent out to allow the complete disengagement of the cap and the bottle. My invention distinguishes from bottle openers made of comparatively soft metal which are pulled upwardly and by main force the cap is pulled off without first levering part of the crimps into an open position. It also distinguishes from openers which are soldered or otherwise secured to the cap and also from devices in which the wire of the opener extends across the neck of the bottle between the cap and the packing and those in which

a wire or the like is secured in a groove in the bottle neck.

Although my invention is of a simple character it will nevertheless be apparent that the opener may be considerably changed in shape and may be made of a single strip of metal, a plurality of flat strips, or a simple wire as shown, or of other suitable design. It is also obvious that it may be connected to the cap in any suitable manner or merely held by the crimping of the cap. Such various changes in my invention will be within the spirit of my invention as set forth in the description, drawings and claims.

Having described my invention, what I claim is:

1. A crimp cap opener comprising in combination a bottle, a cap having a crimped flange, an opener formed of strip material having a reverse bend, the two sides of the strip engaging underneath the crimp of the cap at a considerable distance apart circumferentially of the bottle neck and the crimp 25 to bend the flange outwardly a considerable distance circumferentially.

2. A crimp cap opener comprising in combination a bottle, a cap having a depending flange with crimps, an opener formed of strip material having a reverse bend, the two sides of the strip being caught underneath the flange a considerable distance apart circumferentially of the flange and the bottle neck, the ends of the strip being detached 30 from the cap and positioned to lever against the extreme upper end of the bottle in pulling the reverse bend part upwardly to bend the flange outwardly a considerable distance circumferentially.

40 3. A crimp cap opener comprising in combination a bottle, a cap having a flange with a crimp, an opener having a reverse bend, the two sides of the opener being caught between the flange and the bottle neck, the free ends of the strip being bent to fit the angle formed by the flange and the top portion of the cap.

4. A crimp cap opener comprising in combination a bottle, a cap having a top portion and a depending flange with crimps, a packing fitted against the top, an opener formed of strip material having a reverse bend, the two sides of the strip being caught between the flange and the bottle, the free 55 ends being bent to fit the angle formed by the top and the flange portion of the cap and being positioned between the packing and the top.

5. A crimp cap opener comprising in combination a bottle, a cap having a top with a depending flange having crimps, an opener formed of strip material having a reverse bend, the two sides of the strip being caught between the flange and the bottle 65 neck a considerable distance apart circum-

ferentially, the free ends of the strip being bent towards each other, and fitting the angle formed by the top and the flange.

6. A crimp cap opener comprising in combination a bottle, a cap having a top and a depending flange with crimps, a packing fitting against the top, an opener formed of strip material having a reverse bend, the two sides of the strip being caught between the flange and the bottle neck a considerable 70 distance apart circumferentially of the flange, the free ends of the strip being bent towards each other and fitting the angle between the top and the flange, and between the packing and the top.

7. In the art described the combination of a bottle cap having a top and a flange with crimps, a packing fitted against the top, an opener formed of strip material having a reverse bend, the two sides of the strip fitting against the flange and the free ends being detached from the cap and engaged by the packing partly circumferentially at the angle between the top and the flange.

8. In the art described the combination of a bottle cap having a top and a flange with packing fitted against the top, an opener formed of strip material having a reverse bend, the two sides of the strip fitting inside the flange and spaced a considerable distance apart circumferentially of the flange, the free ends of the strip being loose from the cap and fitting partly circumferentially between the packing and the top at the angle of the top and the flange.

9. In the art described the combination of a bottle cap having a top and a flange with crimps, a packing fitted against the top, an opener formed of strip material having a reverse bend, the two sides of the strip fitting inside the flange a considerable distance apart circumferentially of the flange, the free ends of the strip being bent towards each other and fitting the angle formed by the top and the flange and between the packing and the top.

10. A crimp cap opener comprising in combination a bottle, a cap having a top and a crimped flange with packing against the top, an opener formed of stiff wire having a bend, the two sides of the wire being caught between the flange and the bottle a considerable distance apart circumferentially, the free ends of the strip being loose from the cap and positioned to lever downwardly on the outer periphery of the packing thereby forcing same against the extreme top of the bottle and bending a portion of the flange outwardly on pulling upwardly on the reverse bent portion of the wire, such wire being sufficiently stiff to bend a part of the flange outwardly circumferentially for a considerable distance without substantially bending the wire.

11. A crimp cap opener comprising in

- combination a bottle with a bead at the upper portion of the neck, a cap having a top with a depending flange with crimps, an opener formed of strip material having a 5 reverse bend, the two sides of the strip being caught between the flange and the bottle neck a considerable distance apart circumferentially, the free ends of the strip being bent towards each other and fitting the angle formed by the top and the flange, the 10 opener functioning as a lever and having a fulcrum against the top of the bottle, and being adapted to distort a number of the crimps between the two sides of the strip to 15 free said crimps from the bead on the bottle, the free ends of the strip which are bent towards each other forming a resilient lever thrusting against the top of the cap adjacent the flange.
- 20 12. A bottle opener comprising in combination a bottle having a smooth ungrooved
- neck, a cap having a top with a crimped flange, a packing sheet fitted between the top of the cap and the top of the bottle neck, an opener formed of a stiff wire strip having a 25 bend, the two sides of the strip fitting underneath the flange against the smooth bottle neck, the free ends of the strip being detached from the cap and positioned between the top of the cap and the packing sheet, 30 and said free ends being positioned to lever downwardly on the edge of the packing sheet, pressing said edge against the top of the neck when the bent end of the strip is pulled upwardly, said wire being sufficiently 35 stiff to bend the crimps of the flange outwardly without substantially bending the wire.

In testimony whereof I have signed my name to this specification.

FRANK L. DARLING.
